UNITED STATES PATENT OFFICE.

LAWSON G. HUNTINGTON, OF NEW YORK, N. Y., ASSIGNOR OF ONE-HALF
TO THEODORE B. OSBORNE, OF PLAINFIELD, NEW JERSEY.

LANTERN.

SPECIFICATION forming part of Letters Patent No. 276,182, dated April 24, 1883.

Application filed December 7, 1882. (No model.)

To all whom it may concern:

Be it known that I, LAWSON G. HUNTINGTON, a citizen of the United States, residing in the city of New York, county of New York, 5 and State of New York, have invented certain new and useful Improvements in Lanterns, fully described and represented in the following specification and the accompanying drawings, forming a part of the same.

10 This invention relates to what are known as "loose-globe lanterns," or lanterns in which the globe is not permanently secured to its support, but is capable of being removed for cleaning or for the purpose of inserting a new 15 one in case of breakage.

It has been found in practice that the globes furnished for this class of lanterns vary slightly in size, which makes it necessary to construct the frames large enough to receive the largest 20 globe, and consequently so large that the smaller globes fit loosely and rattle in the frame. To prevent this rattling these lanterns have been provided with an adjustable globe-holder consisting of a band located inside the dome and adapted to fit over the end 25 of the globe, and provided with means by which it can be adjusted vertically to different positions, so that when the globe is inserted in the frame the band can be brought to bear against 30 the end to hold it securely in position. The adjustment of the globe-holding band has usually been effected by means of inclines, either upon the band or dome, against which work studs or a rod, so that by turning the band it 35 is moved vertically to or from the globe. This means of adjustment has been found objectionable in practice, for the reason that the constant jarring to which a lantern is subjected when in use is liable to move the studs along 40 their inclines, thereby releasing the band and loosening the globe.

It is the object of the present invention, among other things, to overcome this difficulty; and to that end one feature of the invention 45 consists in providing the adjusting-inclines with series of serrations, into which the studs are pressed when the band is adjusted against the globe, and which prevent the studs from being moved except upon the application of a 50 considerable degree of force. In this class of

lanterns it is for various reasons desirable to provide for the removal of the globe through the top of the frame, and for this purpose the reflector, which also carries the dome, is usually hinged to the frame so as to be swung to 55 one side when the globe is to be removed, it being provided with a catch for holding it in position after the globe is inserted. When the reflector is thus hinged to the frame it is of course quite essential that the bail should not 60 be attached to the dome, as when so attached the weight of the lantern is very liable to unfasten the catch. To obviate this difficulty I provide the bail with wire ears of suitable form to be attached to two of the vertical rods of 65 the frame, and of sufficient length to extend upward past the reflector, thus attaching the bail to a rigid part of the lantern, and at the same time keeping its body far enough below the point of union with the bail to prevent un- 70 due rocking.

In the accompanying drawings, Figure 1 is a vertical section of the upper portion of a lantern embodying the present invention in one of its forms. Fig. 2 is a side elevation, showing a slightly different embodiment; and Figs. 75 3 and 4 show ears of modified forms.

The globe 1, reflector 2, and frame 3 4 are of an ordinary construction, and therefore require no detailed description. The reflector is attached to the hoop 4 of the frame by the usual hinge, 5, and catch 6, so as to be swung to one side for the introduction and removal of the globe, the hoop 4 being of sufficient size to allow the globe to pass freely. 85

Referring particularly to Fig. 1, it will be seen that the reflector is provided with an upwardly-extending band, 7, through which passes the dome 8, the lower end, 9, of the dome extending sufficiently far downward to 90 encircle and bear against the upper end of the globe. The band 7 is provided with one or more inwardly-extending studs, 10, which rest in inclined slots 11, formed in the lower end of the dome, these slots being provided upon their 95 lower edges with series of serrations 12. The bail 13 is attached to the lantern by means of ears 14, consisting of pieces of wire bent through the eyes of the bail, and having their ends secured to the vertical rods 3 of the frame. 100

The ends of the wires forming the ears may be bent so as to pass upward along said rods, as shown in Fig. 3, and may be also bent around the hoop 4, as shown in Fig. 1; or one end may 5 pass upward and the other downward, as indicated by dotted lines in Fig. 3; or both may extend downward, as shown in Fig. 4. In either case the ears will be secured to the rods 3 by solder or otherwise, and may for additional security be provided with an encircling band, 15. An ear of this construction will be found desirable for other styles of lanterns than that herein shown.

The operation of the apparatus thus constructed will be as follows: The globe having 15 been inserted and the reflector closed and secured by the catch 6, the upper end of the dome will be grasped and turned in its seat, thereby carrying the serrated inclines 12 around 20 beneath the studs 10 and forcing the dome downward, so that its lower end, 9, will encircle and press against the upper end of the globe with sufficient force to prevent the latter from moving or rattling in the frame. In 25 pressing the dome downward against the globe the parts will yield sufficiently to permit the studs to ride over the serrations 12, and will have sufficient elasticity after the dome has been pressed against the globe to hold the studs in 30 the serrations and prevent the dome from mov-

ing except upon the application of considerable force. The range of adjustment afforded by the slots 11 will be sufficient to permit the dome to engage with globes of varying lengths and diameters.

The parts, instead of being arranged as in Fig. 1, may be reversed in order—that is to say, the studs 10 may be located upon the dome and the slots 11 be in the band 7, as shown in Fig. 2. In this case the serrations 12 will of course be upon the upper side of the slots.

What I claim is—

1. The combination, with the removable globe, of the band 7 and vertically-adjustable dome and globe-holder 89, said band and dome 45 being provided with one or more serrated inclined slots, as 11, and studs, as 10, for operating said holder and dome, all substantially as described.

2. The combination, with the lantern-bail 50 and the vertical rods of the frame, of the ears 14, formed from separate pieces of wire bent to the shape shown, substantially as described.

In testimony whereof I have hereunto set my hand in the presence of two subscribing 55 witnesses.

LAWSON G. HUNTINGTON.
